United States Patent Office.

DAVID STODDART, OF SAN FRANCISCO, CALIFORNIA.

Letters Patent No. 79,274, dated June 23, 1868.

IMPROVEMENT IN RECIPROCATING STEAM-ENGINES.

The Schedule referred to in these Letters Patent and making part of the same.

TO ALL WHOM IT MAY CONCERN:

Be it known that I, DAVID STODDART, of the city and county of San Francisco, and State of California, have invented certain Improvements in Direct-Acting Steam-Engines; and I do hereby declare that the following is a full and exact description, reference being had to the accompanying drawings, and to the letters of reference marked thereon, said drawings forming a part of this specification.

Figure 1 is a vertical section through the axis of the steam-cylinder,

Figure 2 is one-half plan, and

Figure 3 is a vertical cross-section through the centre of steam-chest.

A is a steam-cylinder; B¹ B² are two pistons, connected together by the piston-rod; C is a slide-valve; D¹ D² are two small pistons, connected to the slide-valve; E¹ E² are the steam-ports, and F is the exhaust-port, opening into the cylinder between the pistons B¹ B²; G is the opening for the exhaust-pipe. H¹ H² are two small passages, drilled into the cylinder and steam-chest, so as to connect the spaces behind the small pistons to the steam-cylinder. The steam-chest is set transversely to the axis of the cylinder. K¹ K² are two auxiliary passages, similar to H¹ H², but connecting to the cylinder at different places. L¹ L² are partitions, separating the small piston-chambers from the steam-chest, and through which pass the piston-stems, and also a small hole through each to admit steam. These partitions serve as abutments to check the throw of the main valve, and, by the compression of steam between them and the small pistons, an elastic cushion is formed, which obviates any injurious percussion.

The drawings show the engine as in motion, in the direction of the arrows M¹ M², but at the instant when the change of direction is about to take place. The arrows in the various passages show the direction of the currents of live and exhaust steam at the instant before the change of the valve to reverse the stroke.

The action is thus: The slide-valve being in the position in fig. 3, steam is admitted behind main piston B¹, producing motion until opening H¹ is passed, then the steam from the cylinder rushes to the space behind small piston D¹, and reverses the valve, thus admitting steam behind the other main piston B², which produces motion in the reverse direction until opening H² is passed, when the steam rushes to the space behind small piston D², and again changes the valve to the original position. The steam from behind D¹ and D² exhausts back again into the cylinder through the same passages H¹ and H², and the main pistons B¹ B² are set so-far apart that neither can ever entirely blank the main exhaust, or pass more than one opening H¹ or H². The passages K¹ K², shown by dotted lines, are auxiliary, and used for the purpose of preventing a change of valve while the piston is passing across the opening H¹ or H². For if either of the small pistons D¹ or D² should leak, then the pressure behind it might accumulate, while the main piston is passing its connecting-passage, and throw the valve before the proper time, particularly if the engine is working at a slow speed. But the openings K¹ K², connecting the spaces behind D¹ D² to the cylinder, as represented, keep a communication open to the exhaust up to the last instant, for the main piston will just blank the second opening K¹ or K² as it opens the first, H¹ or H². This is an important feature, as a liberal depth of piston may thus be used, and also a slow speed of engine, when required, without affecting the length of the engine-stroke.

The steam-chest is set transversely, because the main steam-ports and passages H¹ H² are more direct than when the steam-chest is in line with the cylinder, and for the further reason that the engine may be used in upright position without the action of gravity interfering with the motion of the valve and pistons D¹ D². It is not new to control steam-valves by steam derived from the cylinder, but in the arrangements heretofore used it is customary to permit the main piston to pass both openings corresponding to H¹ H², but in my invention the general arrangement never permits both of those passages to be closed from the exhaust at one time. Thus I am enabled to produce a positive motion, either slow or fast, and also to obviate any pernicious effects of either natural or undue leakage of any of the pistons or valve.

1. I claim the arrangement of the pistons B¹ B², small pistons D¹ D², valve C, and the passages H¹ H², communicating to the cylinder, substantially as described.

2. I claim the arrangement of the auxiliary passages K¹ K², substantially as described.

DAVID STODDART.
